United States Patent Office

Des. 186,454
Patented Oct. 27, 1959

186,454

FLOWERPOT HOLDER OR SIMILAR ARTICLE

Homer E. Everhard, Wadsworth, Ohio

Application March 25, 1958, Serial No. 50,176

Term of patent 14 years

(Cl. D35—3)

FIG. 1

FIG. 2

Fig. 1 is a perspective view of a flowerpot holder embodying my new design; and

Fig. 2 is a top plan view thereof.

The broken line representation of a flowerpot in Fig. 1 is for illustrative purposes only.

I claim:

The ornamental design for a flower pot holder or similar article, substantially as shown and described.
